AUXILIARY GRIP FOR IMPACT TOOL

CROSS-REFERENCE TO RELATED APPLICATION

The present patent application claims priority to Japanese Patent Application No. 2022-136620, filed Aug. 30, 2022, which is incorporated herein by reference in their entireties for all purposes.

FIELD OF INVENTION

The present invention relates to an auxiliary grip for an impact tool that enhances the shock absorbing function.

BACKGROUND

Conventional auxiliary grips are designed to support a grip body with an elastic material such as a sponge being disposed between the grip base coupled to a tool body to absorb the impact the user's hand. However, there has been a problem with the conventional impact absorbing structure that when a large pressing load to a grip body in an impact direction, the shock absorbing function (anti-vibration function) of the elastic material may be reduced, thereby increasing the strain on the user.

Therefore, there is a need for an improvement of the shock absorbing function of the auxiliary grip. The present disclosure aims to improve the shock absorbing function of the auxiliary grip.

SUMMARY OF THE DISCLOSURE

According to one aspect of the present disclosure, the auxiliary grip for an impact tool may include, for example, a grip shaft extending orthogonally to an impact direction from a tool body being configured for a tool bit to move reciprocally in the impact direction, and a tubular grip body covering the grip shaft. The auxiliary grip for the impact tool may include, for example, a connecting mechanism for connecting the grip body at an end of the grip shaft so the grip body can be slidably in the impact direction.

Therefore, the shock in the impact direction is absorbed as the grip body slidably moves in the impact direction with respect to the grip shaft. This improves the shock absorbing function in the impact direction for the user holding the grip body. As a result, the strain on the user of the impact tool may be reduced.

According to another aspect of the present disclosure, the impact tool may include, for example, an auxiliary grip for an impact tool. This improves the shock absorbing function in the impact direction for the user who uses the impact tool while holding the auxiliary grip body. As a result, the strain on the user of the impact tool may be reduced.

BRIEF DESCRIPTION OF THE DRAWINGS

FIG. 1 is a vertical sectional view of an impact tool.

FIG. 2 is a perspective view of an entire auxiliary grip according to a first embodiment.

FIG. 3 is a right-side view of the auxiliary grip according to the first embodiment, which is a side view as seen from an arrow III in FIG. 2.

FIG. 4 is a vertical sectional view of the auxiliary grip according to the first embodiment, which is a cross-sectional view taken along line IV-IV in FIG. 3.

2

FIG. 5 is a vertical sectional view of a grip shaft and a grip body according to the first embodiment, which is a cross-sectional view taken along line V-V in FIG. 4.

FIG. 6 is a cross-sectional view of a connecting mechanism according to the first embodiment, which is a cross-sectional view taken along line VI-VI in FIG. 4.

FIG. 7 is a cross-sectional view of a second pad according to the first embodiment, which is a cross-sectional view taken along line VII-VII in FIG. 4.

FIG. 8 is a perspective view of the auxiliary grip according to a second embodiment.

FIG. 9 is a right-side view of the auxiliary grip according to the second embodiment, which is a view as seen from an arrow IX in FIG. 8.

FIG. 10 is a vertical sectional view of the auxiliary grip according to the second embodiment, which is a cross-sectional view taken along line X-X in FIG. 9.

FIG. 11 is a vertical sectional view of a grip shaft and a grip body according to second embodiment, which is a cross-sectional view taken along line XI-XI in FIG. 10.

DETAILED DESCRIPTION

25 The embodiments herein and the various features and advantageous details thereof are explained more fully with reference to the non-limiting embodiments that are illustrated in the accompanying drawings and detailed in the following description. Descriptions of well-known components and processing techniques are omitted so as to not unnecessarily obscure the embodiments herein. The examples used herein are intended merely to facilitate an understanding of ways in which the embodiments herein may be practiced and to further enable those of skill in the art to practice the embodiments herein. Accordingly, the examples should not be construed as limiting the scope of the embodiments herein.

In one or more embodiments, the auxiliary grip for the impact tool may include, for example, a first pad provided 40 between an end of a grip shaft and a grip body for absorbing the shock in an impact direction against the grip shaft of the grip body. The shock in the impact direction of the grip body is absorbed by the first pad, which improves the shock absorbing function of the auxiliary grip.

45 In one or more embodiments, the auxiliary grip may include, for example, a second pad provided between a base portion on a side of the tool body of the grip shaft and a grip body to absorb the shock in the impact direction against the grip shaft of the grip body.

50 Therefore, the shock in the impact direction of the grip body is absorbed by the second pad, which improves the shock absorbing function of the auxiliary grip to reduce the shock.

In one or more embodiments, for example, the second pad 55 may include a lateral side adjacent to a grip shaft in a direction orthogonal to the impact direction and a vertical side having a thickness thicker than the lateral side and being adjacent to the grip shaft in the impact direction.

Therefore, the shock in the impact direction is more reliably absorbed by the vertical side of the second pad.

In one or more embodiments, for example, the grip shaft may be provided with a third pad that is harder than the second pad and comes into contact with the grip body after the second pad has deformed.

65 Therefore, when the shock exceeding the shock absorbing function of the second pad is applied to the grip body, a direct contact of the grip body with the grip shaft may be

avoided by the third pad. As a result, the shock impact can be fully absorbed by the absorbing function of the auxiliary.

In one or more embodiments, for example, the connecting mechanism may have a contact surface provided on at least one of the grip shaft or the grip body so as to extend in the impact direction with which the other comes into contact.

Therefore, the grip body supported by the grip shaft can be slideable in the impact direction when the other one of the grip shaft or the grip body contacts with the contact surface.

In one or more embodiments, for example, the connecting mechanism may include a passing through hole for the grip shaft to pass in the direction that is orthogonal to the impact direction, and a connecting member extending through the passing through hole and connected to the grip body. For example, the connecting member may have a flat surface as a contact surface that is parallel to the impact direction, while the passing through hole of the grip shaft has a receiving surface as a contact surface facing the flat surface of the connecting member.

Therefore, the connecting member moves in parallel to the impact direction (radial direction of the connecting member) without rotating about an axis so as to come slidably in contact with the receiving surface, causing the grip body to slide in the impact direction. As a result, the shock in the impact direction is absorbed.

In one or more embodiments, for example, the passing through hole of the grip shaft may have a long groove hole shape elongated in the impact direction, and a receiving surface on an inner surface of the passing through hole.

Therefore, the simply structured connecting mechanism ensures sliding movement with respect to the grip shaft of the grip body.

In one or more embodiments, for example, the connecting mechanism may include a passing through hole for the grip shaft to pass through in the impact direction, and a connecting member passing through the passing through hole and to be connected to the grip body.

Therefore, the movement of the connecting member in the passing through hole of the grip shaft in the impact direction (axial direction of the connecting member) causes the grip body to slide with respect to the grip shaft in the impact direction, thereby absorbing the shock in the impact direction.

In one or more embodiments, the grip body has an elastomer layer on at least an outer surface in the impact direction, and the elastomer layer is integrally formed with a resin layer that is harder than the elastomer layer.

Therefore, the shock in the impact direction is also absorbed by the elastomer layer, thereby reducing the strain on a user.

As shown in FIG. 1, an auxiliary grip 1 attaches to an impact tool 50, which refers to a hammer drill. The impact tool 50 is a relatively large handheld tool that includes a tool body 51, which has an impact mechanism 60, and a loop-shaped handle 52. Also referred in FIG. 1 is a plurality set of a vibration damping mechanism 53 being disposed between the tool body 51 and the handle 52 for providing a vibration damping structure that is elastically supported rather than rigidly coupled in between. The vibration damping mechanism 53 is mainly composed of a compression coil spring to absorb the shock generated on the side of the impact mechanism 60 of the tool body 51 and to prevent the shock from being transmitted to the side of the handle 52.

Still in FIG. 1, the tool body 51 includes a body housing 54. The impact mechanism 60 is mounted within the body housing 54 and includes an electric motor 61 as a drive source. The electric motor 61 is supported in a vertical

orientation with a motor axis M positioned parallel in an up/down direction. The rotational output of the electric motor 61 is transmitted to an intermediate shaft 63 via a bevel gear 62. The intermediate shaft 63 is rotatably supported about the axis J in a lateral orientation with the axis J positioned parallel in a front/rear direction.

Still in FIG. 1, the rotation of the intermediate shaft 63 causes a power conversion member 64 to tilt in a front/rear direction. The power conversion member 64 is connected to a piston 65. Therefore, when the intermediate shaft 63 rotates, the piston 65 reciprocally moves in the front/rear direction. Due to the air pressure generated by the reciprocal movement of the piston 65, a striker 66 moves forward and comes into contact with an intermediate piece 68. The intermediate piece 68 strikes a rear end of the drill bit B. The striking force of the intermediate piece 68 causes the drill bit B to be struck toward a workpiece W. In the present embodiment, the axis of the drill bit B corresponds to an output axis P. The drill bit B is struck forward (impact direction) along the output axis P.

Still in FIG. 1, the rotation of the intermediate shaft 63 causes a tool holder 67 to rotate about the output axis P. A rear side of the tool holder 67 has a cylindrical shape. The piston 65 and the striker 66 are reciprocally accommodated on an inner circumferential side of the tool holder 67. The drill bit B is removably attached to a front side of the tool holder 67. The drill bit B projects forward from a chuck 55 provided at a front part of the main housing 54. The rotational output of the electric motor 61 provides a rotational motion about the output axis P and the striking motion in the direction of the output axis P to the drill bit B that is attached to the tool holder 67.

Still in FIG. 1, the handle 52 has a loop shape extending over between an upper rear side and a lower rear side of the tool body 51. The handle 52 has a grip 56 for a user to actually hold and a pedestal 57. The grip 56 is provided to extend upwardly from the rear part of the pedestal 57. An upper part of the grip 56 is connected to the upper rear side 35 of the tool body 51 via the vibration damping mechanism 53.

Still in FIG. 1, a switching lever 58 is provided at the front side (inside the loop) of the grip 56. A switch body 59 is mounted inside the rear side of the switch lever 58. When the switch lever 58 is pulled rearward with a fingertip of a hand holding the grip 56 (for example, right hand), the switch body 59 is turned ON to activate the electric motor 61.

Still in FIG. 1, a battery mount 71 for mounting a single battery pack 70 is provided on a lower side of the pedestal 57. The battery pack 70 is a slide mounting-type lithium ion battery having a rectangular parallelepiped shape, which is allowed to slide forward with respect to the battery mount 71 to be mounted. The electric motor 61 is activated with the electric power of the mounted battery pack 70 as a power source. A controller 72 having a rectangular flat plate shape 50 is mounted inside the pedestal 57. The controller 72 mainly controls the operation of the electric motor 61.

Still in FIG. 1, the impact tool 50 is used by a user holding a grip 56 of the handle 52 with one hand (e.g. right hand) and the auxiliary grip 1 with the other hand (e.g. left hand). The auxiliary grip 1 is mounted on a cylindrical grip mounting portion 54a provided at the front of the body housing 54. The auxiliary grip 1 mounted to the grip mounting portion 54a extends in a direction intersecting the impact direction (output axis P).

FIGS. 2 to 4 show the auxiliary grip 1 removed from the grip mounting portion 54a. The auxiliary grip 1 includes a grip shaft 10 and a grip body 20. The grip shaft 10 extends

from the grip mounting portion 54a in a direction substantially orthogonal to the impact direction.

As shown in FIG. 2, an elongated circular flange 10b is integrally formed at an upper part of the grip shaft 10. An annular tightening portion 10a is integrally formed on a top of the flange 10b. The tightening portion 10a is displaced in a diameter reduction direction by tightening a fixing screw 11. Tightening the fixing screw 11 with the grip mounting portion 54a positioned on the inner circumferential side of the tightening portion 10a allows the grip shaft 10 to be coupled with the grip mounting portion 54a.

Still in FIG. 2, a plurality of engagement recesses 10c is provided on the inner circumferential side of the tightening portion 10a. The position of the grip shaft 10 about the output axis P is fixed when an engagement projection 54b on the side of the grip mounting portion 54a (see FIG. 1) is fitted into any one of the engagement recesses 10c.

As shown in FIGS. 2 and 3, the tightening portion 10a is elastically deformed in a diameter increasing direction by loosening the fixing screw 11. This loosens the connection of the tightening portion 10a with respect to the grip mounting portion 54a such that the auxiliary grip 1 can be removed from the grip mounting portion 54a. Further, loosening the connection of the tightening portion 10a with the grip mounting portion 54a makes it possible to change the position of the grip shaft 10 around the output axis P. The fixing screw 11 with the position changed is tightened, causing the engagement projection 54b to fit into another engagement recess 10c, thereby fixing the position of the grip shaft 10. This allows the auxiliary grip 1 to arbitrarily change from its vertical orientation (the orientation shown in FIG. 1) extending downward from the grip mount portion 54a to the lateral orientation extending to the left or right.

As shown in FIGS. 3 to 5, the auxiliary grip 1 is provided between an end of the grip shaft 10 and the grip body 20, and includes the first pads 24, 25 configured to absorb the shock in the impact direction on the grip shaft 10 of the grip body 20. The shock in the impact direction of the grip body 20 is absorbed by the first pads 24, 25, thereby improving the shock absorbing function of the auxiliary grip 1.

As shown in FIG. 4, the grip body 20 is connected to the grip shaft 10 at its lower end via the connecting mechanism 12. The lower end of the grip shaft 10 is provided with a two-sided width portion 10d having left and right flat surfaces 10da and 10db at its lower end. Left and right connecting pedestals 20b and 20c are integrally formed at the lower end of the grip body 20. The two-sided width portion 10d of the grip shaft 10 enters between the left and right connecting pedestals 20b and 20c.

Still in FIG. 4, the left and right connecting pedestals 20b and 20c are provided with supporting holes 20d and 20e, which are coaxial with each other. The left and right supporting holes 20d and 20e are formed in a circular hole through which the connecting member 21 can be inserted. One passing through hole 10e is formed in the two-sided width portion 10d of the grip shaft 10.

As shown in FIGS. 4 and 5, the grip body 20 has a tubular shape that covers around the grip shaft 10. The grip body 20 is supported by the grip shaft 10 below the flange 10b. An opening 20a that opens laterally to form a curve is provided at the upper part of the grip body 20. The opening 20a is substantially covered with the flange 10b of the grip shaft 10. An upper end of the grip body 20 has a laterally increasing diameter to improve the gripping comfort of the auxiliary grip 1.

Still in FIGS. 4, 5 and 7, a second pad 28 is disposed between the opening 20a of the grip body 20 and a base 10h

of the grip shaft 10 on the side of the tool body 51. The second pad 28 has an elongated circular shape with a vertical side 28a adjacent to the grip shaft 10 in the front/rear direction (impact direction) and a lateral side 28b adjacent to the grip shaft 10 in the left/right direction. The thickness d1 of the vertical side 28a is greater than the thickness d2 of the lateral side 28b ($d1 > d2$). The second pad 28 absorbs the shock mainly on the upper side of the grip body 20. The second pad 28 is formed to have the thickness d1 on the vertical side 28a greater than the thickness d2 of the lateral side 28b, thereby increasing the shock absorbing capacity particularly in the front/rear direction (impact direction).

Still in FIGS. 4 and 5, a third pad 29 is attached to the grip shaft 10 below the second pad 28. The third pad 29 is attached over the entire circumference of the grip shaft 10. For example, an O-shaped rubber ring may be used for the third pad 29. When the grip body 20 is subjected to the shock that exceeds the shock absorbing capacity of the second pad 28, the grip body 20 comes into contact with the third pad 29. This prevents the grip body 20 from coming directly in contact with the grip shaft 10. As a result, the shock absorbing capacity of the auxiliary grip 1 can be increased.

Still in FIGS. 4 and 5, the grip shaft 10 is provided with a third pad 29 that is harder than the second pad 28 and comes into contact with the grip body 20 after the second pad 28 has elastically deformed. When the grip body 20 is subjected to the shock exceeding the shock absorbing capacity of the second pad 28, the third cushion 29 prevents the grip body 20 from coming directly in contact with the grip shaft 10. As a result, the shock absorbing capacity of the auxiliary grip 1 may be improved.

Still in FIGS. 4 and 5, the connecting mechanism 12 includes a passing through hole 10e for the grip shaft 10 to pass in a direction orthogonally to the impact direction, and the connecting member 21 passing through the through hole 10e and being connected to the grip body 20. The connecting member 21 is provided with flat surfaces 21a, 21b that are parallel to the impact direction. The receiving surfaces 10f, 10g of the passing through hole 10e come slidably in contact with the flat surfaces 21a, 21b. The connecting member 21 is therefore allowed to move in parallel in the front/rear direction within the passing through hole 10e with the rotation about an axis restricted. This allows a lower of the grip body 20 to be connected to the lower part of the grip shaft 10 to be slidable in the front/rear direction.

Therefore, the grip body 20 is allowed to slide in the impact direction as the connecting member 21 moves in parallel in the impact direction (radial direction of the connecting member 21) without rotating about the axis. As a result, the shock in the impact direction is absorbed.

Still in FIGS. 4 and 5, the passing through hole 10e of the grip shaft 10 may have a long groove hole shape elongated in the impact direction. Receiving surfaces 10f, 10g are provided on an inner surface of the passing through hole 10e. Therefore, the simply structured connecting mechanism 12 ensures the sliding movement with respect to the grip shaft 10 of the grip body 20.

As shown in FIGS. 4 to 6, the passing through hole 10e penetrates the two-sided width portion 10d from left to right. FIGS. 5 and 6 show the passing through hole 10e has a long groove hole shape elongated in the front and rear directions. FIGS. 4 and 5 show flat receiving surfaces 10f and 10g that are parallel to each other located on the top and bottom of the passing through hole 10e.

Still in FIGS. 4 to 6, a single connecting member 21 is inserted to extend over between the left and right supporting holes 20d, 20e and the passing through hole 10e. As the

parallel upper and lower flat surfaces 21a, 21b are provided on the connecting member 21, the connecting member 21 is allowed to move in parallel in the front and rear directions within the passing through hole 10e while the rotation about the axis is restricted. A lower part of the grip body 20 is connected to a lower part of the grip shaft 10 via the connecting mechanism 12 with this configuration to be slidable in the front and rear directions.

As shown in FIGS. 6 and 7, left and right ends of the connecting member 21 project into the recesses 20f, 20g formed on the grip body 20. The recesses 20f, 20g are covered with respective caps 22, 23. The caps 22, 23 cover the left and right ends of the connecting member 21. The lower part of the grip body 20 is provided with an enlarged diameter portion 20h with the diameter enlarged to form a curved shape. The left and right caps 22, 23 are fitted into the recesses 20f, 20g so as not to project along the curved shape of the enlarged diameter portion 20h. The enlarged diameter portion 20h restricts the lower end of the grip portion of the grip body 20, thereby improving the gripping comfort of the auxiliary grip 1.

As shown in FIGS. 1, 2, 3 and 5, the front and rear sides of the grip body 20 are covered with the elastomer layers 26, 27, respectively. The elastomer layers 26, 27 serve to prevent the user's hands from slipping and to absorb the shock in the impact direction. The elastomer layers 26, 27 cover only the front and rear sides of the grip body 20, and the left and right sides are not covered with the elastomer layer. The elastomer layers 26, 27 are integrally formed with the grip body 20, which is a harder resin layer.

As shown in FIG. 5, the auxiliary grip 1 is disposed between the base 10h of the grip shaft 10 on the side of the tool body 51 and the grip body 20. The second pad 28 absorbs the shock in the impact direction on the grip shaft 10 of the grip body 20. The thickness d1 of the vertical side 28a of the second pad 28 is formed to have a greater thickness (d1>d2) than the thickness d2 of the lateral side 28b, thereby improving the shock absorbing capacity in the impact direction.

As shown in FIG. 6, the shock in the impact direction is absorbed at the connecting mechanism 12 of the auxiliary grip 1 as the grip body 20 slidably moves in the impact direction with respect to the grip shaft 10. This improves the shock absorbing function in the impact direction for the user holding the grip body 20. The connecting member 21 extends in the left/right direction with respect to the grip shaft 10 and moves in the radial direction (front/rear direction), thereby causing the grip body 20 to slide in the impact direction. As a result, the strain on the user of the impact tool 50 may be reduced.

As shown in FIG. 5, the grip body 20 has elastomer layers 26, 27 on a front surface and a rear surface (outer surface in the impact direction). Therefore, the shock in the impact direction may also be absorbed by the elastomer layers 26, 27, thereby further reducing the strain on a user.

As shown in FIGS. 8 to 11, an auxiliary grip 2 according to the second embodiment is illustrated. The auxiliary grip 2 of the second embodiment is mounted on the cylindrical grip mounting portion 54a provided at the front of the body housing 54 similar to the first embodiment. The auxiliary grip 2 of the second embodiment includes a grip shaft 30 and a grip body 40. The grip shaft 30 extends from the grip mounting portion 54a in a direction substantially orthogonal to the impact direction.

As shown in FIGS. 8 to 10, an elongated circular flange 30b and an annular tightening portion 30a are integrally formed at an upper part of the grip shaft 30. The tightening

portion 30a displaces in a diameter reduction direction by tightening a fixing screw 31. Tightening the fixing screw 31 with the grip mounting portion 54a positioned on the inner circumferential side of the tightening portion 30a allows the grip shaft 30 to couple with the grip mounting portion 54a.

Still in FIGS. 8 to 10, a plurality of engagement recesses 10c is provided on the inner circumferential side of the tightening portion 30a. A position of the grip shaft 30 around the output axis P is fixed when an engagement projection 54b on the side of the grip mounting portion 54a (see FIG. 1) is fitted into any one of the engagement recesses 10c.

As shown in FIG. 9, by loosening the fastening screw 31, the connection of the tightening portion 30a to the grip mounting portion 54a is released so that the auxiliary handle 2 can be removed from the grip mounting portion 54a. Further, loosening the connection of the tightening portion 30a with the grip mounting portion 54a makes it possible to change the position of the grip shaft 30 around the output axis P.

As shown in FIGS. 10 and 11, the grip body 40 has a tubular shape that covers around the grip shaft 30. The grip body 40 is supported by the grip shaft 30 below the flange 30b. An opening 40a that opens laterally to form a curve is provided at the upper part of the grip body 40. The opening 40a is substantially covered with the flange 30b of the grip shaft 30. An upper end of the grip portion of the grip body 40 with a laterally increasing diameter improves the gripping comfort of the auxiliary grip 2.

As shown in FIG. 10, the grip body 40 is connected to the grip shaft 30 at its lower end via the connecting mechanism 32. The lower end of the grip shaft 30 is provided with a two-sided width portion 30d having left and right flat surfaces 30da and 30db at its lower end. The left and right connection pedestals 40b and 40c are integrally formed at the lower end of the grip body 40. The two-sided width portion 30d of the grip shaft 30 enters between the left and right connecting pedestals 40b and 40c to be relatively deformable in the front/rear direction.

Still in FIG. 10, a passing through hole 30e is formed in the two-sided width portion 30d of the grip shaft 30. The passing through hole 30e is positioned with its axis being parallel to the flat surfaces 30da, 30db of the two-sided width portion 30d. One connecting member 33 is inserted into the passing through hole 30e. The connecting member 33 is inserted to be movable in the axis direction with respect to the passing through hole 30e.

As shown in FIG. 11, a narrow portion 30f is provided at the lower part of the grip shaft 30 with its width narrowed in the front/rear direction. The narrow portion 30f is formed with the lower part of the two-sided width portion 30d narrowed in the front/rear direction. The connecting member 33 projects forward and rearward from the narrow portion 30f.

Still in FIG. 11, supporting pedestals 40d, 40e are provided at the front and rear of the lower inner circumference of the grip body 40. The narrow portion 30f of the grip shaft 30 enters between the support pedestals 40d, 40e. The interval between the front and rear supporting pedestals 40d, 40e is determined to allow the narrow portion 30f to be displaceable in the front/rear direction by a sufficient distance.

Still in FIG. 11, front and rear portions of the connecting member 33 are supported by the front and rear supporting pedestals 40d, 40e. The connecting member 33 is non-movably supported to the supporting pedestals 40d, 40e in the axial direction. Both the front and rear ends of connecting member 33 project into the recesses 40f, 40g formed in

the grip body 40. The recesses 40f, 40g are covered with the caps 41, 42, respectively. The caps 41, 42 cover the left and right ends of the connecting member 33. The lower part of the grip body 40 is provided with an enlarged diameter portion 40h with the diameter enlarged forming a curved shape. The left and right caps 41, 42 are fitted into the recesses 40f, 40g so as not to project along the curved shape of the enlarged diameter portion 40h.

Still in FIG. 11, first pads 43, 44 are disposed between a front side of the two-sided width portion 30d of the grip shaft 30 and the grip body 40 as well as between a rear side of the two-sided width portion 30d and the grip body 40, respectively. The first pads 43, 44 absorb the shock in the impact direction on the grip body 40.

Still in FIG. 11, second pads 45, 46 are disposed between the opening 40a of the grip body 40 and the base 30g of the grip shaft 30 on the side of the tool body 51. The second pads 45, 46 are disposed on the front side and the rear side of the impact direction with respect to the base 30g of the grip shaft 30. The front and rear second pads 45, 46 absorb the shock mainly on the top side of the grip body 40.

Still in FIG. 11, a third pad 47 is attached to the grip shaft 30 below the second pads 45, 46. The third pad 47 is attached over the entire circumference of the grip shaft 30. For example, an O-shaped rubber ring may be used for the third pad 47. When the grip body 40 is subjected to a shock exceeding the shock absorbing capacity of the second pads 45, 46, the grip body 40 comes into contact with the third pad 47. This allows the grip body 40 to avoid coming directly in contact with the grip shaft 30. As a result, the shock absorbing capacity of the auxiliary grip 2 can be improved.

As shown in FIGS. 8, 9, 11, the front and rear sides of the grip body 40 are respectively covered with the elastomer layers 48, 49. The elastomer layers 48, 49 serve to prevent slippage of the user's hands and absorb the shock in the impact direction. Similar to the first embodiment, the elastomer layers 48, 49 only cover the front and rear sides of the grip body 40, and the left and right sides are not covered with the elastomer layer. The elastomer layers 48, 49 are integrally formed with the grip body 40, which is a harder resin layer.

As shown in FIGS. 9 to 11, the shock in the impact direction is absorbed at the connecting mechanism 32 of the auxiliary grip 2 as the grip body 40 slidably moves in the impact direction with respect to the grip shaft 30. This improves the shock absorbing function in the impact direction for the user holding the grip body 40. As a result, the strain on the user of the impact tool 50 may be reduced.

As shown in FIGS. 10 and 11, the connecting mechanism 32 includes a passing through hole 30e for the grip shaft 30 to pass through in the impact direction and a connecting member 33 inserted into the passing through hole 30e so as to be displaceable in the axial direction. The connecting member 33 moves within the passing through hole 30e of the grip shaft 30 in the impact direction (axial direction of the connecting member 33) to cause the grip body 40 to slide in the impact direction with respect to the grip shaft 30. As a result, the shock on the grip body 40 is absorbed.

Still in FIGS. 10 and 11, the connecting member 33 extend in the front/rear direction with respect to the grip shaft 30 and move in the axial direction (front/rear direction), thereby causing the grip body 40 to slide in the impact direction.

Although a hammer drill that strikes while rotating the drill bit B is illustrated herein as an impact tool, the illustrated auxiliary grips 1 and 2 may be applied to any

impact tools that merely strike against the tool bit, such as hammer tools used, for example, for chipping work. Further, the connecting mechanisms 12, 32 may be applied to any auxiliary grips that are removable from any tool body.

5 The impact tool may be either a DC machine using a rechargeable battery pack 70 as a power source or an AC machine utilizing a commercial power source.

The auxiliary grip 1 of the first embodiment and the auxiliary grip 2 of the second embodiment are some examples of auxiliary grips for an impact tool in one aspect of the present disclosure. The drill bit B of the first and second embodiments is one example of a tool bit in one aspect of the present disclosure. The tool body 51 in the first and second embodiments is one example of a tool body in 15 one aspect of the present disclosure.

The front side in the first and second embodiments is one example of the impact direction in one aspect of the present disclosure. The grip shaft 10 in the first embodiment and the grip shaft 30 in the second embodiment are some examples of the grip shaft in one aspect of the present disclosure. The grip body 20 in the first embodiment and the grip body 40 in the second embodiment are some examples of the grip body in one aspect of the present disclosure. The connecting mechanism 12 in the first embodiment and the connecting mechanism 32 in the second embodiment are some examples of the connecting mechanism in one aspect of the present disclosure.

The various examples described above in detail with reference to the attached drawings are intended to be representative of the present disclosure and are thus non-limiting embodiments. The detailed description is intended to teach a person of skill in the art to make, use and/or practice various aspects of the present teachings, and thus does not limit the scope of the disclosure in any manner. 30 Furthermore, each of the additional features and teachings disclosed above may be applied and/or used separately or with other features and teachings in any combination thereof, to provide an improved auxiliary grip for an impact tool, and/or methods of making and using the same.

40 What is claimed is:

1. An auxiliary grip for an impact tool comprising:
a tightening portion along an outer surface of a tool body configured for a tool bit to reciprocally move in an impact direction;
a fixing member extending between ends of the tightening portion and being configured to close together the ends for the tightening portion to secure the outer surface of the tool body;
a grip shaft extending from the tightening portion in a direction orthogonally to the impact direction;
a tubular grip body being configured to cover the grip shaft; and
a connecting mechanism being configured to connect the grip body at an end of the grip shaft, and
a guide surface provided at the grip shaft and facing in a left-right direction orthogonally to an extension direction of the grip shaft and orthogonally to the impact direction;
wherein the grip body is slidable along the guide surface in the impact direction against the grip shaft and is restricted from moving in the left-right direction by the guide surface.
2. The auxiliary grip of claim 1, further comprising a first pad disposed between the end of the grip shaft and the grip body to absorb a shock in the impact direction against the grip shaft of the grip body.

11

3. The auxiliary grip of claim 2, further comprising a second pad disposed between a base of the grip shaft on a side of the tool body and the grip body to absorb a shock in the impact direction against the grip shaft of the grip body.

4. The auxiliary grip of claim 3, wherein the second pad includes a lateral side being adjacent to the grip shaft in a direction orthogonally to the impact direction and a vertical side having a greater thickness than the lateral side, wherein the vertical side being adjacent to the grip shaft in the impact direction.

5. The auxiliary grip of claim 3, further comprising a third pad being configured to come into contact with the grip body when the second pad has elastically deformed.

6. The auxiliary grip of claim 5, wherein the third pad is provided on the grip shaft.

7. The auxiliary grip of claim 5, wherein the third pad is harder than the second pad.

8. The auxiliary grip of claim 1, wherein:
the connecting mechanism includes a connecting member passing through the grip shaft in the left-right direction wherein left and right ends of the connecting member are connected to the grip body,
the guide surface is formed with an elongated hole in the impact direction in which the connecting member is inserted, and
the connecting member is slidable in the impact direction along the elongated hole so that the grip body slides against the grip shaft in the impact direction.

9. The auxiliary grip of claim 1, wherein the connecting mechanism includes a connecting member passing through

12

the grip shaft in the impact direction, and wherein the grip body is slidable along the connecting member in the impact direction.

10. The auxiliary grip of claim 1, wherein:
the grip body includes an elastomer layer on at least one outer surface in the impact direction, and
the elastomer layer is integrally formed with a resin layer, and wherein the resin layer is harder than the elastomer layer.

11. An auxiliary grip for an impact tool for enhancing a shock absorbing function, the auxiliary grip comprising:
a grip shaft being configured for a tool bit to reciprocally move in an impact direction;

a tubular grip body being configured to cover the grip shaft;
a connecting mechanism being configured to connect the grip body at an end of the grip shaft, wherein the grip body is slidable in the impact direction; and
a plurality of pads for absorbing the shock, wherein the plurality of pads comprises

a first pad disposed between the end of the grip shaft and the grip body to absorb a shock in the impact direction against the grip shaft of the grip body,

a second pad disposed between a base of the grip shaft on a side of a tool body and the grip body to absorb a shock in the impact direction against the grip shaft of the grip body, and

a third pad being configured to contact with the grip body when the second pad has elastically deformed.
